UNITED STATES PATENT OFFICE

FREDERICK C. OVERTURBURY, OF HILLSDALE, NEW JERSEY, ASSIGNOR, BY MESNE ASSIGNMENTS, TO THE PATENT AND LICENSING CORPORATION, OF BOSTON, MASSACHUSETTS, A CORPORATION OF MASSACHUSETTS

METHOD OF AND MACHINE FOR MAKING ROOFING ELEMENTS OF ASSORTED COLORS

Application filed April 21, 1926. Serial No. 103,667.

This invention relates to fabricated roofing elements of the type known as strip shingles and has to do particularly with the production of multi-colored strip shingles in a variety of color combinations. My invention is thus not limited to any particular shape or material of roofing element nor to any kind or class of coloring materials. One type of roofing element to which my invention is readily applicable is the strip shingle made of waterproofed felt. Elements of this type are usually made by saturating and coating a sheet of felted fibrous material with suitable waterproofing compounds, and surfacing the sheet partly or wholly with grit, such as crushed slate, sand, or other granular material. The sheet is cut or otherwise divided into individual units or elements at any desired point in the process, each element having a plurality of shingle-simulating elements of any desired shape and size. In making shingle strips, the butts of individual shingles of any desired shape are usually simulated on the portion of the strip which will be exposed to view when laid, by dividing this portion by indicia, such as slots, grooves or distinguishing lines of some kind defining tabs therebetween. These lines of division form the pattern on the roof giving the appearance of single spaced shingles. The roof may be given any desired color by the choice of grit applied to the tabs in surfacing the coated areas which are to be exposed. A roof of a single color, however, presents a monotonous appearance. To avoid such monotony and to give the roof a more pleasing and artistic appearance, a plurality of colors have been applied to roofing elements in various ways. Many methods of color application to the elements have resulted in streaks, blotches or geometrical designs on the roof as a whole when laid, all of which detract from the appearance of the roof. It has been found that artistic and pleasing effects may be obtained by applying a variety of harmonizing colors to the strips, the boundaries between adjacent colors coinciding with the slots or lines separating the shingle-simulating tabs, and the strips being laid so that the colored tabs appear in haphazard ar-

rangement on the roof. To secure this effect with shingle strips, it is necessary that the sequence or arrangement of colors in the individual strips be varied, otherwise a certain undesirable regularity of design is inevitable on the laid roof. It is not necessary, however, that every pair of consecutive tabs be of different colors. Successive tabs may frequently be of the same color, the important feature being that the various colors are not gradually blended into each other but are sharply defined by definite boundaries, these boundaries closely coinciding with lines of division between successive tabs. An object of my invention is to provide means for making shingle strips having tabs of different colors. Another object of my invention is to provide a machine which will produce successive strips having a variety of assortments of colors on the tabs. This saves the trouble and expense of making up assortments from different lots of similar strips.

Further advantages and improvements will appear on the drawing, in which:

Figures 1 and 1a represent diagrammatically in elevation apparatus for carrying a sheet of roofing material from the supply roll through the various operations to the finished product.

Figure 2 is a perspective of the cutter roll on a larger scale.

Figure 3 is a fragmentary plan of a sheet of roofing material showing the relative arrangement of slits, cuts, color bands, and tab-distinguishing slots or marks.

Figure 4 represents a typical shingle strip cut from the sheet.

Referring to the drawing in detail, 10 represents a supply roll suitably supported from which a sheet 11 of roofing material may be supplied. This sheet 11 may be of any desired width or material. In making roofing of this general type, such sheet material is customarily formed on paper-making machines and is composed of fibrous material comprising rag or asbestos fibers or the like. The felted fibrous sheet is made sufficiently absorbent to be readily saturated with liquefied bitumen or equivalent saturant, after which it is customarily coated with an im-

pervious coating material, such as high melting-point asphalt, liquefied by heat, to which may be applied a protective surfacing of comminuted or granular material. As shown in Figure 1, the sheet 11 may first be led through a slotting device 12 which cuts out parallel series of slots 13 suitably spaced to distinguish shingle-simulating tabs on the finished product. By cutting slots in the raw felt, the material cut out can be returned to the beater and used over again. Instead of cutting slots on the sheet as shown the slots may be pre-formed during the making of the sheet or in any other desired way. The step of slotting also may be omitted, or replaced by a device for cutting a groove, marking a line, or otherwise distinguishing successive shingle tabs.

20 The sheet of felt 11 is led through a container 14 filled with suitable saturating liquid, the excess saturant being pressed out as by a pair of rolls 15. The saturated sheet may now be cut longitudinally into strips by a suitable slitting device 16. It is obvious that 25 the slitter may if desired be positioned to operate on the sheet before it is saturated instead of afterward as shown. The strips of the sheet may then be led beneath a coating device which as shown comprises a spout 17, 30 rolls 18 to spread the coating material evenly, and a receptacle 19 to catch excess coating which may flow through the slots and between the strips. For coating the strips I 35 preferably use "blown" or oxidized asphalt on account of its tough and rubbery consistency and its relatively high melting point. The asphalt may be applied by heating to fluidity or may be applied cold in the form of an emulsion, such as that described in the 40 patent to Kirschbraun No. 1,417,835. Instead of the asphalt, I may use any other equivalent impervious compound. By slitting the sheet into strips before the coating operation, the coating material will flow over 45 the edges of the strips and the cut-outs, thus sealing the cut edges and protecting the cut ends of the fibers from the weather. If the strips have not been slotted prior to coating, grooves or channels may be pressed, 50 gouged, or otherwise formed in the coating layer to define shingle-simulating tabs. Instead of applying the coating to the upper surface, I may, if desired, apply it by suitable means to the lower surface or to both 55 surfaces of the sheet. While the coating material is still tacky, the sheet is led beneath a slating device conventionally indicated at 20. This device may be of any desired structure capable of depositing on the moving 60 sheet transverse bands of different colored comminuted material. Any number of colors may be applied. On the drawing, four hoppers, each with a different color, are indicated, the feeding mechanism within the hoppers being intended to operate intermittently 65

in such a way that all the hoppers drop granular material on the moving sheet while the sheet progresses through a distance equal to the width of a shingle division. Then the flow of grit ceases while the sheet further progresses a distance equivalent to the width of four shingle divisions. Thus in one complete cycle of operation of the hoppers, the strip advances a total distance of five shingle widths, one during the showering of the grit, and four during the period of inaction of the hoppers. Since the hoppers cover only four of the five shingle widths during one cycle of operation, bands of one shingle width will be left blank between successive grit-covered areas. Material from the hoppers which falls through the slots and between the edges of these strips may be caught by a suitable receptacle 21. A fifth hopper 22 is preferably supplied to pour granular material over the whole sheet continuously. This covers the band of coated area which has been left blank and also any spaces which have accidentally failed to receive grit from one of the four hoppers. The sheet may then be led around suitable rolls 23, 24, which press the grit into firm engagement with the coated areas. Excess grit not adhering to the sheet will fall from the roll 23 and be caught by a suitable receptacle 25 from which it may be supplied to the hopper 22. As the grit so caught includes grit from all four of the hoppers 20, the color supplied through the hopper 22 will with this arrangement of mechanisms be a mixed or neutral color. The sheet may then be led over a series of pressing rolls 26 which may also cool the sheet if the coating has been applied hot. The sheet may be further cooled, if desired, by any preferred type of refrigerator conventionally indicated at 27. The strips may now be cut into separate roofing elements, preferably of a length to include a plurality of shingle-simulating tabs. The elements are preferably cut from the slit strips of the sheet 11 by cutting blades 28 suitably mounted on a roll 29. The roll 29 is preferably adjusted with reference to the color bands on the sheet so that each cut on a strip coincides with a boundary between two successive bands of color. The cutters 28 for the different strips are arranged at different points on the periphery of the roll 29 in such a way that the cuts on the several parallel strips will come in a staggered or echelon formation longitudinally of the sheet as shown clearly in Figure 3. This staggering of the cuts produces at once an assortment of color combinations on the finished elements, so that the necessity for forming assortments from supplies of different kinds of strips is obviated. It is also advantageous to have a greater number of colors on the sheet than the number of tabs on a finished element. It will be clear that the greater the number of colors that

can be applied to the sheet, the greater will be the variety of color combinations on the finished units cut from the sheets. The 5 strips may be collected in a suitable container or conveyor 30 and assembled for shipment.

The order of steps in the process may be changed around to a considerable extent. By 10 following the sequence shown in the drawing and hereinbefore described, shingle strips can be produced, the exposed portion of which, including the edges, is completely covered with a protective coating of impervious material surfaced by suitable granular material 15 in a variety of colors, each individual color area coinciding with a section of the strip which is equivalent to one shingle. These strips will come from the machine in a variety of color combinations which will permit packing 20 of the strips directly from the machine.

It may be noted that my invention comprises a combination of four distinct methods of obtaining an assortment of color combinations, any one of which would alone provide 25 assorted arrangements of colors, assuming that as hereinbefore described the colors are applied in regularly recurring series of bands. First, by providing a number of colors differing from the number of tabs on 30 each element. In this case, the elements cut from each continuous strip would have an assortment of combinations. This effect could be obtained also by cutting successive elements with a varying number of tabs from 35 a continuous strip. Thus, if the sheet were slated with three colors A, B, C, A, B, C, etc., two-tab strips would have the combinations A B, C A, and B C. Four-tab strips would have A B C A, B C A B, and C A B C. It 40 is obvious that the greater the number of colors, the wider will be the variety of combinations. Second, by cutting the slots or other tab indicators so that adjacent continuous strips in the sheet lie butt to butt or head 45 to head, the combinations in adjacent strips will be reversed, e. g., if as before bands of three colors A, B, C, are applied to the sheet, even if three-tab elements be cut from the strips the combinations A B C and C B A 50 will be obtained. Another element of variety in color tones is produced by this method due to the fact that when crushed slate of a solid color is applied to a sheet in the usual machine for making roofing elements, the color tone 55 of the slate surfacing varies according to the direction from which it is viewed. Hence, if two elements be cut from a uniformly slated sheet and one of them turned around so that its upper and lower edges exchange positions, the color effects presented by the two 60 elements will be distinctly different, though both are surfaced with the same material. Third, by staggering the cuts severing the elements from the several continuous strips, a 65 further assortment is obtained in assembling

all the elements from the sheet as they come from the machine. In this case, elements would be taken successively from the several strips in rotation. Fourth, a further assortment may be had by adding to the apparatus shown a second multiple color slating device 70 arranged to operate on the reverse surface of the sheet so that each individual element would have different combinations on its two faces. It is obvious that the more of the four methods described are used together, the wider will be the variety of color combinations obtainable. 75

Having thus described an embodiment of my invention it should be apparent to those skilled in the art that various changes and modifications may be made therein without departing from its spirit and scope as defined by the appended claims. 80

I claim:

1. The method of making roofing elements with different combinations of colored areas, which comprises applying a number of different colors in rotation in successive transverse bands to a strip of sheet roofing material, and cutting off elements from said strip, each pair of successive cuts on the strip being spaced by the width of a number of bands less than the number of colors applied to the strip. 85

2. The method of making multi-colored roofing elements, which comprises applying surfacing material of different colors to a sheet of roofing material in transverse bands of shingle width, slitting the sheet longitudinally into strips, successive strips being disposed head to head and butt to butt, and cutting off elements from said strips, each pair of successive cuts on a strip being on color boundaries and spaced by the width of a plurality of said bands. 95

3. The method of making multi-colored roofing elements, which comprises forming in a sheet of roofing material indicia to define shingle-simulating tabs, surfacing a face of the sheet with transverse bands of various colors, each of the boundaries between different colors registering with one of said indicia, slitting the sheet longitudinally in such a manner relatively to said indicia that adjacent strips will be disposed butt to butt and head to head, and cutting roofing elements from said strips, each comprising a plurality of tabs. 100

4. The method of making multi-colored roofing elements, which comprises surfacing a sheet of roofing material with transverse bands of different colors, slitting the sheet longitudinally into strips, and cutting the strips on lines coinciding with boundaries between color bands, said cuts of the several strips being staggered longitudinally of the sheet. 110

5. The method of making multi-colored roofing elements, which comprises slitting a 115

- sheet of roofing material longitudinally into strips, coating and dividing into shingle-simulating tabs a longitudinal portion of each strip, applying bands of different colors transversely across all said strips, cutting roofing elements from the strips, each element having a number of tabs differing from the number of colors on the strips, the cuts of the several strips being staggered relatively longitudinally of the sheet.
6. The method of making multi-colored roofing elements, which comprises slitting a sheet of roofing material into strips, defining shingle-simulating tabs on said strips, applying impervious coating material to a face of each strip and the edges thereof, applying bands of different colored materials transversely across the entire sheet, the successive color bands coinciding with successive tabs, and cutting elements from said strips, each element comprising a plurality of tabs, the cuts being on lines between successive tabs and the cuts of the several strips being staggered relatively longitudinally of the sheet.
7. The method of making shingle strips, which comprises slotting, saturating, longitudinally slitting and coating a continuous sheet of roofing material, applying colored grits to a coated face of the strip in transverse bands, the boundaries between successive colors registering with the slots in the sheet, and cutting elements from the slit strips, the lines of cut on the different strips being relatively staggered longitudinally of the sheet and being made on boundaries between adjacent color bands.
8. The method of making multi-colored roofing elements, which comprises forming in a sheet of roofing material indicia to define shingle-simulating tabs, surfacing a face of the sheet with transverse bands of various colors, each of the boundaries between different colors registering with one of said indicia, slitting the sheet longitudinally in such a manner relatively to said indicia that adjacent strips will be disposed butt to butt and head to head, and cutting roofing elements from said strips, the cuts of the several strips being made in echelon.
9. The method of making multi-colored roofing elements, which comprises forming in a sheet of roof material indicia to define shingle-simulating tabs, surfacing a face of the sheet with transverse bands of colors, each of the boundaries between different colors registering with one of said indicia, slitting the sheet longitudinally in such a manner relatively to said indicia that adjacent strips will be disposed butt to butt and head to head, and cutting off multi-tab roofing elements from said strips, the number of tabs on each element being different from the number of colors on the sheet.
10. The method of making multi-colored roofing elements, which comprises forming in a sheet of roofing material indicia to define shingle-simulating tabs, surfacing a face of the sheet with transverse bands of various colors, each of the boundaries between different colors registering with one of said indicia, slitting the sheet longitudinally in such a manner relatively to said indicia that adjacent strips will be disposed butt to butt and head to head, and cutting off multi-tab roofing elements from said strips, each element having a number of tabs differing from the number of colors on the sheet, the cuts of the several strips being made in echelon.
11. In a machine of the class described, means for slitting a sheet of roofing material longitudinally into strips, means for applying different colors to said sheet in transverse bands, and means for cutting off elements from the several strips, said cutting means including separate transverse knives for the several strips, said knives being offset with respect to each other by distances which are multiples of the width of one of said color bands.
12. In a machine of the class described, means for slitting longitudinally a sheet of roofing material into strips, means operating on each strip to define shingle-simulating tabs, means for applying different colors to successive areas of each of the strips, the boundaries between adjacent color areas coinciding with the boundaries between adjacent tabs, and means for cutting said strips transversely on certain of said boundaries.
13. In a machine of the class described, means for surfacing a sheet of roofing material with materials of different colors arranged in transverse bands, and means for cutting from the sheet roofing elements having areas of different colors, said cutting means including means for cutting the sheet lengthwise across the color bands and means for making transverse cuts shorter than the width of the sheet on boundaries between successive color bands.
14. In a machine of the class described, the combination with means for cutting series of slots in a continuous sheet of roofing material, means for progressively saturating said sheet with liquid bitumen, means for slitting said sheet longitudinally, and means for applying impervious coating to a face of the sheet, of means for applying granular material in transverse bands of various colors to the coated face of the sheet, the boundaries between adjacent colors passing through said slots, and means for cutting roofing elements from the slit strips, the cuts on the several strips being relatively staggered lengthwise of the sheet and all being made on boundaries between adjacent colors.
- In testimony whereof I have affixed my signature.
- FREDERICK C. OVERBURY.
